UNITED STATES PATENT OFFICE.

HENRY A. SMITH, OF ATLANTA, GEORGIA.

DESIGN FOR A BADGE.

SPECIFICATION forming part of Design No. 25,467, dated May 12, 1896.

Application filed April 29, 1895. Serial No. 547,569. Term of patent 3½ years.

To all whom it may concern:

Be it known that I, HENRY A. SMITH, a citizen of the United States of America, and a resident of Atlanta, in the county of Fulton and State of Georgia, have made a certain new and useful Design for Badges; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

The drawing shows a front elevation of the pendant.

This design consists of a miniature bale A, of cotton fiber, packed and pressed into shape and covered by a suitable covering a, representing as near as may be the ordinary jute bale-cloth which is used in baling cotton, and held in shape by metallic ties or bands a', the image of a negro eating a section of watermelon seated on said bale, and another section of melon on said bale by his side.

In the design as shown the broad side of the bale is seen, the bale being edge up in position, although of course I do not wish to confine myself to that exact position. On the left-hand front corner of the bale is seated the figure of a negro B, holding in his hand, as if eating, a piece of watermelon b, while on the bale at the left of the figure is a second piece of watermelon b'. Above the bale and secured thereto by links c or other suitable means of connection is a panel C, which may be engraved with any desired lettering or design.

Having thus described my design, what I claim as new, and desire to secure by Letters Patent of the United States, is—

The design for a badge substantially as herein set forth.

In testimony whereof I hereunto affix my signature in presence of two witnesses.

HENRY A. SMITH.
